UNITED STATES PATENT OFFICE.

JOHN WESLEY SAUER, OF LEXINGTON, KENTUCKY.

DISPLAY BOX.

Application filed January 26, 1927. Serial No. 163,705.

This invention relates to new and useful improvements in boxes for displaying cigars, candy and the like, and has for its primary object to provide a false bottom together with means for enabling the raising of the bottom so that the box may have the appearance of being substantially filled, with the end that all the goods therein will be readily purchased by the public.

10 The invention further aims to provide simple and inexpensive means whereby the false bottom may be moved upwardly to a predetermined degree within the box, and rigidly maintained in such a position.

15 With the foregoing and other objects in view as the nature of the invention will be better understood, the same comprises the novel form, combination and arrangement of parts hereinafter more fully described,

20 shown in the accompanying drawing and claimed.

In the drawing wherein like numerals indicate like parts throughout the several views:

25 Figure 1 is a top plan view of an open box constructed in accordance with the present invention.

Figure 2 is a detail longitudinal section therethrough for more clearly disclosing the 30 manner of supporting the false bottom therein as well as the manner of permitting the same to be readily raised or lowered.

Figure 3 is an elevation of one end of the box, and

35 Figure 4 is a perspective of a pin member to which the raising wire or cord is attached so as to facilitate the securing of the pulling end of the cord or wire to the bottom or end of the box for maintaining the false bottom in raised position.

Now having particular reference to the drawing, 5 indicates the body of a conventional cigar, candy or the like box, including a bottom wall 6, side walls 7-7 and end walls 8-8. The invention further consists of a false bottom wall 9 of a size to enable the same to be readily raised and lowered within the box but yet to substantially fill a horizontal area within said box.

50 The end walls 8-8 of this box are formed

adjacent their upper edges and at their opposite ends with openings 10-10 in substantially horizontal alignment as indicated in Figure 2. Furthermore, the false bottom 9 is formed adjacent its four corners with 55 openings 11, and secured through the openings 10-10 of one end wall 8 are the opposite ends of a predetermined length of fine wire or cord 12, which cord or wire is thence extended downwardly through the openings 60 11 at the adjacent end of the false bottom 9 after which the same is extended horizontally beneath the false bottom and thence passed upwardly through the openings in the opposite ends thereof, and through the 65 openings 10 in the opposite end wall of said box 5. Secured to the cord or wire at the center thereof is a thumb tack or other suitable pin fastener 13 adapted for forcible engagement within the end or bottom wall of 70 the box as clearly indicated in Figure 2. Obviously after the false bottom 9 has been raised by pulling upon the center of the cord or wire and thence forcing the pin fastener 75 into the box, the false bottom 9 will be maintained at a predetermined elevated position within said box with the result that the purchaser of the goods labors under the impression that insomuch that the goods upon the false wall are arranged at the top of 80 the box there must be one or more layers of the goods remaining, and therefore such raised goods are still in fresh condition.

Having thus described the invention, what I claim is:

The combination with a cigar box having a bottom, side and end walls, each of the end walls being formed with a pair of openings adjacent the upper edge thereof and adjacent the front and rear sides of the box; 90 of a false bottom loosely arranged within the box, and provided with an opening at each corner, a length of cord bent back upon itself intermediate its ends, the free ends of the cord extending upwardly through the 95 openings at one end of the false bottom, and through the adjacent openings in the adjacent end wall of the box, the extremities of the cord being secured to said end of the box adjacent the respective openings formed 100

therein, the intermediate portions of the cord being disposed beneath the false bottom adjacent the respective side edges thereof, said cord extending upwardly through the opening in the opposite end of the false bottom and through the openings in the adjacent end wall of the box, and a pin fas-

tener permanently carried by the bend in the cord for forcible engagement with the outside of the box for supporting the false bottom in any vertically adjusted position in the cigar box.

In testimony whereof I affix my signature.

JOHN WESLEY SAUER.
